UNITED STATES PATENT OFFICE

144,609

DESIGN FOR A WASHING MACHINE RECEPTACLE

Fred A. Conterman, Jamestown, N. Y., assignor to
Jamestown Metal Equipment Company, Inc.,
Jamestown, N. Y., a corporation of New York

Application July 19, 1944, Serial No. 114,448

Term of patent 14 years

(Cl. D49—1)

To all whom it may concern:

Be it known that I, Fred A. Conterman, a citizen of the United States, residing at Jamestown, in the county of Chautauqua and State of New York, have invented a new, original, and ornamental Design for a Washing Machine Receptacle, of which the following is a specification, reference being had to the accompanying drawing, forming part thereof; and in which

Fig. 1 is a plan view of a washing machine receptacle showing my new design;

Fig. 2 is a side elevational view of the receptacle shown in Fig. 1; and

Fig. 3 is a fragmentary vertical sectional view

taken substantially as indicated by the line 3—3 of Fig. 1.

The design for a washing machine receptacle is characterized by the specific configuration shown wherein a depressed flat, ring-like area is formed centrally of the base and the side walls are plane surfaced, and an inturned rim is radially offset from the plane of the side walls, all as shown.

I claim:

The ornamental design for a washing machine receptacle, substantially as shown and described.

FRED A. CONTERMAN.
